Atlys.

UNITED STATES PATENT OFFICE.

MONROE KEETON, OF MERIDIAN, MISSISSIPPI.

FIRECRACKER-HOLDER.

1,362,705.

Specification of Letters Patent. Patented Dec. 21, 1920.

Application filed October 23, 1920. Serial No. 419,154.

To all whom it may concern:

Be it known that I, MONROE KEETON, a citizen of the United States, and resident of Meridian, in the State of Mississippi, have 5 invented certain new and useful Improvements in Firecracker-Holders, of which the following is a specification.

My invention relates to fire cracker holders, its principal object being the provision 10 of a device of the above character which will reduce to a minimum the danger co-incident with the use of fire crackers by children or others. A further object is to provide a device which will permit fire crackers of comparatively large size and explosive force to be used without danger of injury from sparks, fragments or the concussion caused by the explosion.

A further object is to provide a fire cracker holder which is attractive and durable, and which can be cheaply manufactured.

My invention consists in the novel construction, arrangement of parts and details as set forth in the annexed specification and illustrated in the accompanying drawing, in which—

Figure 1 is a side view of my device;

Fig. 2 is a front view thereof;

Fig. 3 is a side view showing a modification of my improved holder; and

Fig. 4 is a front view of the device of Fig. 3.

Referring now to the drawing, the numeral 1 designates as a whole, a resilient clamping member, which is secured to a handle A of any desired length. The member 1 is preferably formed from a single blank of resilient material, such as sheet metal, bent into substantially U-shape, and having its ends bent outwardly as at 2 to form guard portions 3 and 4. The angles 2 of the member 1 form the jaws of the clamp, and are normally held in engagement with each other through the natural resiliency of the material. The guard portion 3 has portions 3^a pressed inwardly and bent in circular form to provide fastening means or an operating lever 5 by which the jaws of the clamp may be separated for the insertion of a fire cracker. The guard member 4 has inwardly pressed portions 4^a bent similarly to the portions 3^a, to form fasten-

ing means for the ends of a wire 6 which encircles the handle A by a series of loops 6^a at points adjacent the end thereof. The guard 55 portions 3 and 4 may be provided at their meeting edges, with curved depressions 7 adapted to bear against the fire cracker and prevent its lateral displacement in the holder.

In the modified form of my invention shown in Figs. 3 and 4, I provide a substantially rectangular guard 10, curved outwardly, and having portions 10^a pressed out and bent in circular form for receiving the 65 ends of a wire 11 by which it is secured to the handle A, and is also provided with extensions 12 adjacent the middle of each side, which are turned outwardly and to which are suitably secured the ends of a coiled 70 wire spring 13. In this form, the fire cracker, or several fire crackers, are placed between the coils of the spring 13.

In the operation of my invention in its preferred form, the operating lever 5 is depressed, and a fire cracker inserted between the jaws 2. The device is then held outwardly from the body in the hand of the operator by means of the handle A and the fire cracker ignited. When the explosion 80 occurs, it will be readily seen that by reason of the pinching action of the clamp 1 on the lower end of the fire cracker, and the guards 3 and 4, any sparks or fragments will be prevented from reaching the person holding 85 the device. Furthermore, by my invention, fire crackers of greater size and explosive force may be used in comparative safety.

What I claim is:

1. A fire cracker holder comprising a handle, a resilient clamp attached to one end of said handle and adapted to receive a fire cracker, said clamp having outwardly turned extensions beyond its normally meeting edges to form guards. 90

2. A fire cracker holder comprising a handle, a resilient clamp attached to one end of said handle, and adapted to receive the lower end of a fire cracker, said clamp having outwardly turned extensions from its meeting edges 100 forming guards, and means for separating the meeting edges of said clamp.

In testimony whereof I affix my signature.
MONROE KEETON.
